SEWING MACHINE CABINET

William H. Clingman, Grand Rapids, Mich., assignor to
The Singer Manufacturing Company, Elizabeth, N. J.,
a corporation of New Jersey

Application August 10, 1955, Serial No. 37,398

Term of patent 14 years

(Cl. D33—12)

Fig. 1.

Fig. 2.

Fig. 1 is a front perspective view of a sewing machine cabinet showing my new design.

Fig. 2 is a rear perspective view of the sewing machine cabinet shown in Fig. 1.

The characteristic feature of my design resides in the combinations on the sewing machine cabinet disclosed of the smooth panels above the legs in association with the specific front, drawer effect door, all as shown.

I claim:

The ornamental design for a sewing machine cabinet, substantially as shown and described.
